UNITED STATES PATENT OFFICE.

JOHN E. SCHLIEPER, OF PITTSBURGH, PENNSYLVANIA.

TINNING APPARATUS.

Application filed May 29, 1920. Serial No. 385,114.

To all whom it may concern:

Be it known that I, JOHN E. SCHLIEPER, a citizen of the United States, residing at Pittsburgh, in the county of Allegheny and 5 State of Pennsylvania, have invented a new and useful Improvement in Tinning Apparatus, of which improvement the following is a specification.

My invention relates to improvements in 10 tinning apparatus and particularly to mechanism for feeding the sheets through the tinning bath.

The object of my invention is to produce a mechanism for this purpose, in which 15 simplicity of construction is attained, with a maximum degree of efficiency.

I accomplish the object of the invention by means of the apparatus hereinafter more 20 fully described, reference being had to the accompanying drawings, forming part hereof, in which:

Fig. 1 is a plan view of the apparatus.

Fig. 2 is a section on lines II—II of Fig. 1.

Fig. 3 is a detail of one pair of the feed 25 rolls and their connections.

Fig. 4 is a sectional elevation on lines IV—IV of Fig. 1.

Fig. 5 is a vertical section through the tinning bath parallel with the rolls, and be- 30 tween the driving rolls and the set of rolls adjacent.

Fig. 6 is a transverse vertical section of the tinning vessel and frame, the rolls and other parts being omitted.

35 Referring to said drawings, I show a receptacle of the usual construction, adapted to contain tinning material, i. e., the tinning material and the flux, and is divided, as shown in the drawings, into two com-

40 partments, 2, 3, which are connected by means of the guide conduit or orifice, 4, which extends widthwise and corresponds with the interior width of the apparatus.

The said compartments, 2, 3, are adapted, as 45 heretofore stated, to contain the tinning material, the forward portion of the compartment, 3, containing the flux used in initially treating the sheets before they enter the tinning material. The sheet feeding mecha-

50 nism comprises a table, 5, located at the forward end, and is provided with regulating stops, 6, which are adapted to be adjusted or positioned to accommodate any required size of plate. Adjacent the lower side of 55 said table, a pair of drying rolls, compris-

ing the rolls 7 and 8, are located, the said rolls being supported in suitable housings, 9, formed in the sides of the frame 29. These rolls are preferably formed of rubber, for the purpose of excreting or removing moisture from the plates fed thereto from the table, 5. The plates are fed from said rolls into and through the two sets of rolls, which comprise the rolls, 10, 11, 12, 13 arranged tandem in said vessel, each set having a 60 driven roll. The bearing ends, 14, 15, of said rolls, 10, 12, and also the bearing end, 16, of the roll, 7, project through the side walls of a frame, 29, seated in said compartment, 3, the ends of each of said bearings respectively being provided with cranks, 17, 18, the said cranks being connected by rods, 19, 20. It is noted that the cranks on one side are arranged on a different angularity than those on the opposite 65 side, the cranks on one side projecting in an opposite direction to the cranks on the opposite side. The lower rolls of each set are frictionally driven from the upper rolls, which are positively driven through the rotation of the cranks, which are driven from the sprocket wheels, 21, 21, which are mounted upon the ends respectively of the roll, 7, a belt, 22, or other suitable means being employed to drive said sprocket wheels. The 70 upper rolls of each set are adjustably maintained in their housings by means of the springs, 23, the tension of which holds said rolls in proper relation with the lower rolls 75 and thereby adjusts and regulates the pressure upon the plates fed between the rolls and through the tinning material by the action of the upper or top rolls. Guides, 24, are arranged to support the plates in their 80 passage through the tinning material. A 85 spray pipe, 25, is positioned along the lower side of the table, 5, and the water that is sprayed upon the tinning sheets is adapted to be discharged before the passage of said sheets into the first set of rolls, through the 90 discharge opening, 26, in the forward end of the compartment, 3. The sheets, after 95 passing through the tinning bath, are forced or passed through the conduit, 4, which connects the two compartments, 2 and 3, 100 and are carried through the conduit, 27, into and through the finishing rolls, 28, the said rolls being located in the upper end of the compartment, 2, in suitable housings. 105 The sheet feeding mechanism is supported 110

in the side members of the frame, 29, the upper side members, 31, of said frame being secured in sockets formed in the bar or projection, 32, the upper portion of said frame, 29, having a recess, 33, in its under side, adapted to fit over the upper edge of the casting, forming the front wall of the compartment, 3, and the lower portion of said frame, 29, being secured in the 5 duct or opening, 4, between the compartments, 2 and 3, whereby the said frame is securely seated in the compartment, 3, without bolts or rivets. The sides of said frame within the vessel project low enough in said 10 vessel to form a compartment, X, in which the driving mechanism is located and adapted to operate; or an apron or extension, 30, which may be either secured to or integral with the sides of said frame, projects towards the bottom of said vessel a sufficient 15 distance to form said compartment.

Having described my invention, what I claim and desire to secure by Letters Patent, is:

- 25 1. In a tinning apparatus, the combination of a vessel adapted to contain tinning material, of a sheet feeding mechanism, comprising a plurality of sets of rolls located in said vessel, the bearing ends of the driven roll of each set having a crank mounted thereon, the said cranks being connected, whereby the said driven rolls are rotated in the same direction, to feed the sheets or plates through the tinning bath.
- 30 2. In a sheet tinning apparatus, the combination of a vessel adapted to contain tinning material, of a sheet feeding mechanism comprising a plurality of sets of rolls, the upper roll of each set having a crank mounted on the end thereof, the said cranks on one side of the apparatus projecting in one direction and the cranks on the opposite side projecting in an opposite direction, rods connecting said cranks and means to trans-

mit motion to said cranks, whereby the 45 plates or sheets are fed progressively through the tinning bath.

3. In a tinning apparatus, the combination of a vessel adapted to contain tinning material, a table or platform arranged at 50 the front end of said vessel and provided with adjustable stops for the reception of tin plates placed thereon, in combination with sheet feeding mechanism comprising a series of sets of rolls, the upper roll of each of said sets having a crank mounted on the end thereof, the said cranks being connected, and means to transmit power to said cranks, whereby said rolls are adapted to feed sheets 55 through the tinning bath. 60

4. In a tinning apparatus, the combination of a vessel, a sheet feeding device seated in said vessel, comprising a frame, a series of feed rolls journaled in the side walls of said frame, the said rolls having cranks projecting beyond the side walls and an apron or extension to said side walls extending to a point substantially at the bottom of said vessel. 65

5. In a tinning apparatus, the combination of a vessel, a sheet feeding device seated in said vessel, comprising a frame, a series of feed rolls journaled in the side walls of said frame, the said rolls having cranks projecting beyond the side walls, the cranks on 70 one side of the device projecting in one direction and the cranks at the opposite projecting in an opposite direction, means connecting said cranks; and an apron or extension to said side walls extending to a point 75 substantially at the bottom of said vessel. 80

In testimony whereof, I have hereunto signed my name in the presence of two subscribing witnesses.

JOHN E. SCHLIEPER.

In the presence of—

JOHN H. RONEY,

CLARENCE A. WILLIAMS.
